UNITED STATES PATENT OFFICE.

ADNA F. BLANCHARD, OF PROVIDENCE, RHODE ISLAND.

CATCH FOR JEWELRY.

Original application filed November 19, 1920, Serial No. 425,216. Divided and this application filed August 27, 1921. Serial No. 495,951.

To all whom it may concern:

Be it known that I, ADNA F. BLANCHARD, a citizen of the United States, residing at Providence, in the county of Providence and State of Rhode Island, have invented certain new and useful Improvements in Catches for Jewelry, of which the following is a specification.

This invention is a division of the matter of my application Serial No. 425,216, filed November 19, 1920.

The invention has for an object to effect improvements in the manufacture of flexible bracelet catches, particularly aiming to enable the satisfactory production of such an article from sheet metal in an inexpensive manner. Another important purpose is to provide an improved form of catch or clasp, adapted to be contained within one of the very small units ordinarily employed in such bracelets, whereby all of the units of the bracelet may be of uniform size.

Additional objects, advantages and features of invention will appear from the construction, arrangement and relation of parts hereinafter described and shown in the drawings, wherein.

Figure 1 is an elevational view of a number of units connected, enlarged four diameters.

Fig. 2 is a horizontal sectional view of a unit with the jewel removed and showing a latch bill, instead of the usual link head employed on the other units of a bracelet, greatly enlarged.

Fig. 3 is a similar view of a unit having the usual link head thereon and having incorporated therein, a catch device to coact with the bill before mentioned.

Fig. 4 is a bottom view of a blank for a combined latch link and gem pallet.

Fig. 5 is a plan view of the blank for the clasp or latch spring member shown in Fig. 3, the last two illustrations being enlarged four diameters.

Fig. 6 is a perspective view of the spring frame.

There is illustrated a bracelet including any desired number of links 10 of identical construction, with the exception that one is provided with a latch bill 11 shown in Fig. 2, instead of the link head 12, shown in Fig. 3, and the one other unit next thereto has in addition to the parts of the other units,

a spring latch, provided with a release stem 55 18 projected from one side of the unit.

Each of the units comprises a gem pallet frame 14 formed of a blank of suitable sheet metal of the general form shown in Fig. 4, including an elongated body portion having one end portion 15 bent upward to form a rest wall for the pallet top, the immediately adjacent body portion 16 forming a rectangular base or bottom plate for one of the bracelet units, while the opposite part of the blank is bent upwardly forming a wall 15', parallel to the wall 15, and then inwardly parallel to the plate 16 so that the extremity thereof rests upon the upper part of the wall 15, forming the pallet proper, and is 70 provided with a circular aperture 18 in the present instance sufficiently smaller than the diameter of the gem to be set to permit the gem to be laid therein for support. The blank has extensions from each side on the base 16, one of which is turned upwardly at right angles to the plate, forming a check wall 19, which extends some distance above the pallet 17. At the opposite side there is an extension 21 occupying the full 75 width of the base 16 projected beyond the adjacent edge portion of the blank a distance corresponding to the thickness of the metal in the cap later described, while centrally of this extension there is in one terminal unit a bill 11 having a diagonal end edge 24, as shown in Figures 2 and 4. In the wall portion 19, there is formed a triangular opening 25, to receive a head 12 as described in my said prior application. 80

A cap 26 is provided for each unit, having wall portions 27 adapted to fit snugly around those of the pallet and to close the open side of the pallet element above the extension 21. In the present instance, the cap is rectangular in horizontal section and formed in one piece by extrusion. The cap is formed with an opening 29 of a size to engage slightly over the edge of a circular gem set on the pallet. One wall of the cap is 100 horizontally slotted at its lower part to align with the lower part of the opening 25, as indicated at 30 in Fig. 1, and the opposite wall of the cap is slightly shorter than the remaining walls, in order to rest 105 upon the extension 21, as clearly shown in Fig. 1.

In one unit there is incorporated a spring

latch device 31, shown in Fig. 3, formed from the blank shown in Fig. 5. This blank comprises a plain strap of resilient sheet metal bent to form a nearly rectangular box-like latch frame, which functions like a spring. One end portion of the blank forms a short side 35 of the latch frame and the opposite end portion 36' of the blank is set outwardly at an oblique angle so that the frame is thereby not quite rectangular, and is adapted to serve more efficiently as a spring, as will be subsequently explained. In the lower edge of the spring frame at the short side 35, there is formed a slot 36 stopping short of the adjacent end of the spring, and forming a lock edge 37. On the next adjacent side of the latch frame, which is opposite the portion 36' and projected from its lower edge, there is formed an operating stem or head 13, before mentioned, which is bent outwardly to lie horizontally at right angles to the plane of this side of the spring. It is enlarged and indented on the outer end to enable the ready operation thereof by a finger-nail presented against the end of the stem. The wall portion 15 of the pallet frame of the unit in which the spring is to be incorporated is suitably slotted as at 38' to permit insertion 30 of the stem 13 therethrough, the body of the spring being adjusted to rest upon the plate 16 with the short side 35 extending across the opening 25 and the portion 36' of the spring bearing outwardly against the wall 35 of the pallet frame. The lower edge of the cap member is suitably slotted as at 38', in Fig. 1, to allow downward presentation of the cap around the stem 13 and to permit slight lateral movement of the stem for 40 operation as indicated in Fig. 3, by the dotted lines. It will be seen that the edge member 11 may be engaged with the bill 37 of the spring by simply pressing the pointed part of the bill into the slot 38 through the opening 25, and release may be effected by pressing the operating stem 13 inwardly as indicated in dotted lines in Fig. 3.

If desired, the slot for insertion of the stem 13 through the wall 15 of the pallet frame may be formed in all of the units, as indicated in Fig. 3, its presence being no

detriment to the units when otherwise utilized as indicated.

By having the opening 25 extend into the base plate 16 a distance, a greater range of pivotal movement of the units of the bracelet is permitted, as will be understood.

In the manufacture of the device, the wall 15 of the pallet frame is turned up and the latch frame, previously formed, then put in place on the base 16, the remainder of the frame 14 being formed then, and the parts 14 of the units linked together. Next the gems are laid on the frames 14, and caps put in place, pressed into proper position relatively to the pallets, and the lower lateral edge portions of the caps set inwardly, to retain the parts, as set forth in my prior application.

What is claimed:—

1. A fastening comprising, a hollow member having a bill receiving slot at one side, a leaf spring catch device laid around the interior of the hollow member and expanding to lie closely against the inner sides of the hollow member throughout one end portion disposed across the slot for sliding movement, thereover, and having a bill engaging part normally located before the said slot, an operating stem on the spring projected slidably from the hollow member for operation of the catch device, and a second unit having a bill insertable through the slot to engage the catch.

2. A terminal unit for flexible jewelry comprising a hollow rectangular member having a slot in one side, a spring bent to form an arm slideable adjacent the slot and a part thereon to project over the slot normally from one end, the spring having an end sprung outward to bear against one side of the body adjacent said end of the slot tending to hold the lock part in locking position, and an operating stem on the spring projected slidably from the side of the body opposite the spring end last mentioned.

In testimony whereof I have affixed my signature in presence of two witnesses.

ADNA F. BLANCHARD.
